Primary Examiner — Mary Ann Calabrese*Assistant Examiner* — Catherine Ho(74) *Attorney, Agent, or Firm* — Bush Intellectual Property Law; Kenneth M. Bush(57) **CLAIM**

I claim the ornamental design for a combined permit box and stand, as shown and described.

DESCRIPTION

FIG. 1 is a top, front, right side perspective view of a combined permit box and stand, showing my new design; FIG. 2 is a top, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof. The broken line portion of the figure drawings is included to show portions of the article that form no part of the claimed design.
